UNITED STATES PATENT OFFICE.

CALVIN JACOB ROWE, OF BROWNSVILLE, ILLINOIS.

ROTARY ENGINE.

SPECIFICATION forming part of Letters Patent No. 759,315, dated May 10, 1904.

Application filed June 27, 1903. Serial No. 163,418. (No model.)

To all whom it may concern:

Be it known that I, CALVIN JACOB ROWE, a citizen of the United States, residing at Brownsville, in the county of White and State 5 of Illinois, have invented a new and useful Rotary Engine, of which the following is a specification.

My invention is an improvement in rotary engines, and has for its object to provide an 10 engine of this character which will be durable in construction, easily operated, and in which the various parts will be accessible for repairs without requiring a great amount of labor in removing other parts.

15 In order to secure compactness and protection from dust, many types of rotary engines are inclosed in heavy casings and the various parts fitted one within another, so that in order to repair some valve or replace an abutment, piston-head, or spring it is necessary to take practically the entire machine apart, adding considerably to the time and money required in making repairs. This disadvantage 20 I overcome by arranging the various parts 25 parallelly upon a suitable base, inclosing those parts requiring protection, and so assembling the parts in general that a particular part—a valve, for example—may be taken out and repaired without materially disturbing other 30 parts of the machine.

35 My invention consists of the novel features or combination of parts hereinafter described, particularly pointed out in the claims, and shown in the accompanying drawings, in which—

Figure 1 is a perspective view of my improved engine. Fig. 2 is a vertical section taken through the tubular steam-chamber and slide-valves, the piston-heads being shown in 40 elevation. Fig. 3 is a side elevation, a portion of the engine being broken away to show the construction of one of the slide-valves working in the tubular steam-chamber. Fig. 4 is a section on the line 4 4 of Fig. 3. Fig. 45 5 is a transverse section taken through the tubular steam-chamber, showing the packing-ring and means for securing same in place. Fig. 6 is a detail elevation, partly in section,

showing the reversing-bars. Fig. 7 is a longitudinal section through the main shaft, showing 50 a portion of the cut-off wheel in section and showing in dotted lines one of the reversing-bars. Fig. 8 is a detail elevation showing a strap connected to the packing-ring.

In the construction of my device I employ 55 front and rear base-plates A A'. A casting A² rises from the bases A and supports the tubular steam-chamber B. A vertical casting A³ rises from the base A' and is strengthened by suitable ribs. The circular tubular chamber B is formed in quarter-sections, each section being flanged at each end, as shown at B', the flanges extending outwardly and being elongated on one side of the tube, and the flanges of adjoining sections are bolted together. The central portion of the inner faces of the elongated parts are cut out or reduced in thickness, as shown at B² in Fig. 3, and grooves are formed at the extreme ends of the flanges communicating with the reduced 60 portion. Slide-valves B³ are arranged between adjoining flanges, sliding in the space formed by the reduced portions B², and valve-stems B⁴ attached to the slide-valves and extend outward through the grooves in the ends 65 of the flanges. A rod B⁵ is pivoted at one end to the upper end of the casting A³ and is slotted at the opposite end, a pin on the end of the upper slide-valve engaging the slotted end. On each side of the casting A³ project 70 horizontal arms A⁴, to which are pivotally connected ends of rods B⁶, which are slotted at their opposite ends and engaging outer ends of the horizontally-extending valve-stems B⁴. A rod B⁷, pivoted at its rear end 75 to one of the ribs of the casting A³ and slotted at its forward end, extends between the bases A and engages the outer end of the valve-stem of the lowermost valve B³.

Each of the sections of the chamber B is 80 longitudinally slotted, as shown at B⁸, outwardly-extending parallel flanges B⁹ being formed integral with the edges of the slotted portion, an inner shoulder being formed on each of said flanges.

95 A shaft C is journaled adjacent one end

in the casting A³, and its opposite end is rigidly secured to a wheel C'. The periphery fits and rotates within the slotted portion of the tubular sections forming the steam-chamber. This wheel carries piston-arms C², extending within the chamber B, and piston-heads C³. Extending between these arms are the sections of a packing-ring C⁴, which fits in the slot B⁸, bearing on the shoulders formed 5 on the flanges and rotating with the wheel C'. The central portion of these packing-ring sections between the shoulders bears on the periphery of the wheel C', and to hold the ring firmly in place openings C⁵ are formed in the 10 wheel C', adjacent its periphery, and the sides of the wheel between the openings and the periphery of the wheel are grooved. Stirrups C⁶ fit in these grooves, the ends of each stirrup being secured to the packing-ring and the 15 bow portion lying in one of the openings C⁵. In the bow portion of each stirrup is arranged a coiled spring C⁷, bearing at one end outwardly on the wheel and on the opposite end inwardly with reference to the axis of the 20 wheel on the bow of the stirrup. It will be obvious that the tendency of these springs will be to hold the packing-ring firmly down on the shoulders of the flanges and against the periphery of the wheel. In the form of 25 engine shown the piston-arms are three in number, and the packing-ring is accordingly in a similar number of sections.

To operate the valve-rod B⁵, B⁶, and B⁷, there 30 is rigidly fixed on the shaft C between the casting and the tubular chamber B a wheel D, having formed on its forward face a cam-groove D', the groove being extended outwardly and then inwardly at three equidistant points D², corresponding in number to the piston-heads, 35 and the points D² being the same distance apart as the piston-heads. Pivoted to the valve-rod B⁵, B⁶, and B⁷ and sliding through suitable guide-arms extending horizontally from the casting A³ are rods D³, carrying rollers at their inner ends, the said rollers engaging the grooves. It will be obvious that rotation of the cam-disk D will alternately move 40 the rods D³ inwardly and outwardly, imparting a similar motion to the valve-rod B⁶ and 45 giving the valve-stems B⁴ a reciprocatory motion, each outward and inward movement being followed by a period of rest.

Arranged on the rear side of each quarter-section of the tubular chamber B and adjacent 50 one end thereof is a steam-chest E, and inlet-passages E' give communication between these chests and the interior of the tubular chamber, each passage opening into the steam-chamber adjacent one of the slide-valves B³, 55 the said valves normally dividing the interior of the steam-chamber B into four separate compartments, three of which will have a piston-head projecting within it. Adjacent the

opposite ends of each of the quarter-sections is arranged a steam-chest E², having communication with one of the compartments of the steam-chamber through a passage E³. When the engine is driven in a forward direction, as indicated by the arrow in Fig. 2, steam will be admitted through the passages E' from the 65 chests E, exhausting through the passages E³; but when the motion is reversed by means hereinafter described steam is admitted through the chests E² and passages E³, exhausting through the passages E'. 70

The upper quarter-sections B carry rearwardly-extending brackets F, and supported by these brackets are two steam-chests F' and F², each of which is divided into a lower cylindrical chamber and an upper steam-chamber. In the upper chamber of the chest F' is arranged a slide-valve F³, having an outwardly-projecting valve-handle F⁴. Two ports give communication between the upper and lower portions of the chest F', and the valve 80 F³ is of sufficient length to cover both of said ports when on center, one being closed and one being open when the valve is off center.

Two steam-pipes G and G' lead from the cylinder of the chest F', and in this cylinder 90 is a piston F⁵, having a slide formed integral with it and adapted to close the entrance to one of said pipes.

In the chest F² the cylinder is divided by a transverse partition F⁶, on each side of which 95 are arranged pistons F⁷, each acting as a slide-valve to close a port opening into an exhaust-box F⁸, from which leads an exhaust-pipe F⁹. A steam-pipe F¹⁰ opens into the upper portion 100 of the steam-chest F'. The pistons F⁵ and F⁷ are connected by a common piston-rod F¹¹.

Four steam-pipes H are joined together by suitable elbows to form a square frame, and branch pipes H' lead from the pipes H to the steam-chests E. The upper pipe H is also 105 connected to the lower end of the pipe G and has communication with one end of the cylinder in the chest F² through the pipe G². Arranged within the frame H is a smaller square pipe-frame J, comprising four pipe-sections 110 fitted together, as is the frame H. To this smaller frame of pipes is connected the lower end of the pipe G', previously referred to, and a pipe G³ leads from the upper pipe-section J to the chest F², its upper end opening into 115 the chest on the opposite side of the partition from the pipe G². Steam-pipes J' lead from the chests E² to the pipes J. Arranged on the shaft C immediately in the rear of the pipe-frames is a cam-wheel K, having a 120 groove K' on its forward face, the groove being cut so that the inner portion of the wheel will form a cam having three elevations or projections K². In each chest E E² is arranged a piston E⁴, the rod of each piston being pivoted to an end of a link K³, rigidly se- 125

cured at the opposite end to a rock-shaft K¹, journaled at one end in the rear side of one of the tubular pipe-sections B and having at the opposite end a crank portion carrying a roller 5 traveling in the groove K'.

A flanged collar L is slidingly keyed to the shaft and has pivoted to it on opposite sides crooked bars L', pivoted at their forward ends to a sliding collar L², the bars sliding through 10 openings L³ formed in the wheel K. The bars are crooked sufficiently to rotate the wheel K a distance equal to one-twelfth of its circumference, this rotation being relative to the shaft C. To slide the collar L, a clutch 15 mechanism is arranged as follows: Journaled in a bracket M is a vertical rock-shaft M', to the upper end of which is rigidly secured one end of a crank M², having a lower cranked portion rocking a clutch M³, which slides the 20 collar L toward and away from the wheel K.

When the valve F³ is on center, no steam will be admitted to the engine; but when drawn back, as shown in Fig. 4, steam will pass into the cylinder of the chest F² and move the slide- 25 piston F⁵, so that the upper end of the pipe G' will be closed and the pipe G open. This movement of the piston F⁵ also sets the pistons F⁷ in the chest F² so that the engine will exhaust through said chest, and it further 30 throws the cam-wheel K into the proper position with reference to the shaft to give a forward motion. From the chest F² the steam passes through the pipe G into the pipe-frame H, through pipes H' into the chests E, through 35 the inlet-passages E' into the compartments of the tubular steam-chamber B, driving the piston-heads from right to left, (see Fig. 2,) escaping through the passages E³ into the chests E', through the pipes J' into the frame 40 J, and through pipe G³ to the exhaust-box. When the valve F³ is thrown to the opposite end of the chest F², the upper end of the pipe G is covered and that of the pipe G' uncovered. The collar L is moved toward the wheel 45 K, and the wheel is rotated by the crooked feathering-bars L'. Steam passes through the pipe G' into the pipe-frame J, through pipes J' into the chest E², and by way of the passages E³ into the chambers B, driving the piston-heads from left to right and exhausting 50 through passages E', chests E, pipes H', H, and G², and thence through the exhaust-box of the chest F².

Having thus fully described my invention, 55 what I claim as new, and desire to secure by Letters Patent, is—

1. An engine of the kind described comprising a rotatable shaft, a tubular steam-chamber encircling said shaft, said chamber being 60 longitudinally slotted on the side adjacent the shaft and having parallel flanges extending from the edges of the slot toward the shaft, said flanges being formed with inwardly-ex-

tending shoulders, a wheel on said shaft the periphery of which is adapted to travel within the flanges, arms carried by said wheel said arms extending into the steam-chamber and having piston-heads thereon, packing-strips arranged on the periphery of the wheel between the arms said strips being of greater 65 width than the thickness of the periphery of the wheel and resting between the flanges and on the said shoulders, the wheel having slots formed therein adjacent its periphery, stirrups arranged in said slots, and springs arranged in the stirrups adapted to press same toward the axial center of the wheel and hold the packing-strips firmly down against the periphery of the wheel.

2. In combination with a rotary engine, a 80 central rotatable shaft, a wheel mounted on said shaft and having openings formed in its face and a cam-groove, a plurality of steam-chests, a piston arranged in each chest, a piston-rod extending from each chest, rock-shafts 85 having cranked portions carrying rollers, the said rollers traveling in the cam-groove, a collar slidably keyed to the shaft, crooked bars pivoted to opposite sides of the collar said bars being adapted to slide in the openings formed 90 in the wheel and rotate same with reference to the shaft, and means for sliding the collar.

3. A rotary engine comprising a main shaft, a tubular steam-chamber encircling said shaft, the tubes forming said chamber being slotted 95 along the side adjacent the shaft, a wheel mounted on said shaft and extending into said slots, a packing-ring arranged in the slots, pistons carried by the wheel and traveling in the tubular steam-chamber, slide-valves working 100 in said chamber, steam-chests secured to said chamber, pistons arranged in the steam-chests, a wheel mounted on the shaft and having a cam-groove formed in its face, arms having rollers at their inner ends adapted to engage said groove said arms being adapted to actuate the slide-valves, a second wheel carried by the shaft having a cam-groove formed in its face, a roller adapted to travel in said 105 groove, and means connected to said roller adapted to regulate movement of the pistons.

4. An engine of the kind described comprising a shaft, a tubular chamber formed of quarter-sections, each section having an outwardly-extending flange at each end, said flanges having a central portion reduced in thickness, the flanges of adjacent sections being bolted together, a slide-valve sliding between said flanges and adapted to extend into said tubular chamber, said tubular sections being longitudinally slotted, outwardly-extending parallel flanges formed adjacent the slots, a wheel secured on the shaft and extending between said flanges, piston-heads carried by the periphery of said wheel, a sectional packing-ring arranged in the slotted portion of said 115 120 125

tubular sections and bearing on the periphery of said wheel, and means carried by the wheel for holding said ring in position.

5. A rotary engine comprising front and rear uprights, an annular tubular steam-chamber supported by the front uprights, a shaft journaled in the rear upright and extending forward through the ring formed by the annular tubular chamber, a wheel on said shaft 10 carrying pistons extending into said annular, tubular chamber, valves in said chamber a cam-

wheel on the shaft actuating said valves, steam-chests connected to said tubular chamber, a cam-wheel on said shaft controlling passage of steam through said steam-chests, and reversing mechanism adapted to rotate the last-mentioned cam-wheel with reference to the shaft. 15
